UNITED STATES PATENT OFFICE.

JESSE B. PIATT, OF NEW LEBANON, OHIO.

REINFORCED CONCRETE COLUMN.

Application filed November 27, 1926. Serial No. 151,078.

This invention relates to new and useful improvements in reenforced concrete columns.

It is one of the principal objects of my invention to provide for flues and like structures, an economical and efficient hollow, reenforced concrete column.

It is another object of my invention to make the framework of this column a simple, inexpensive and easily assembled construction. Being composed principally of horizontal tie rods and vertical corner rods, the framework may be easily hooked together from a collapsed state to receive concrete.

When concrete is applied to the framework, an adequate air space will be left between the inner and outer sections. If a double column is not desired, a single one may be readily formed by omitting the inner section.

Other important and incidental objects will be brought out in the following specification and particularly set forth in the subjoined claims.

In the accompanying drawings illustrating my invention, Figure 1 is a perspective view of a double reenforced concrete column, partly broken away to reveal the metal reenforcing members hooked together to form the framework or form. Figure 2 is a perspective view of an inner side section of the reenforcing framework. And Figure 3 is a perspective view of one of the outer side sections of the same.

Referring to the accompanying drawings for a detailed description of my invention, the numerals 1 designate four inner corner rods and the numerals 2 four outer corner rods. At each side of the frame are bent horizontal tie rods 3. Each tie rod 3 has a hook end 4 which engages an inner corner rod 1, a bend 5 that receives the adjacent inner corner rod on the same side of the frame and a hook end 6 which engages the outer corner rod 2 nearest to the last named inner corner rod 1. (See Figures 1 and 2.) In addition to the reinforcement provided by the tie rods 3 at the sides of the frame, straight tie rods 7 are employed. Each one of these rods 7 has hook ends 8, 8 to engage the inner corner rods 1, 1 on its respective side of the frame. As shown in Figures 1 and 2, vertical brace rods 9 are welded to the horizontal tie rods 3 and 7 to hold them in place. Secured to the framework made up of the horizontal and vertical rods just described, is a

metal or card-board backing 10. To this reenforcing frame concrete is applied.

The outside corner rods 2 are themselves connected by straight horizontal tie rods 11 which have hook ends 12 to engage said corner rods. (See Figures 1 and 3.) To these tie rods 11 are welded vertical brace rods 13 to form a framework to which a metal or card-board backing 14 is attached. To this reenforcing frame concrete is applied.

Between the inner and outer concrete sections thus formed an adequate air space is left for the purpose of ventilating and strengthening the entire column.

As will be obvious from the drawings, the inner section of the column may be omitted, leaving the outer section to form a single hollow column.

In the erection of a double column, the inner section is constructed first and coated with concrete. The projecting hook ends 6 of the inner tie rods 3, being of a length to conform to the distance between the companion inner corner rods 1 and the outer corner rods 2, will engage the latter. The framework of the outer section, consisting of the tie rods 11, brace rods 13 and backings 14, is then coated with concrete.

It is thus seen that I have provided a concrete column which may be easily and economically formed.

Having described my invention, I claim:

1. A reenforced concrete column comprising vertical corner rods, horizontal tie rods formed with hook ends for engagement with the corner rods, vertical brace rods secured to the horizontal tie rods, backing means attached to the tie rods and brace rods, and concrete applied to the form composed of said rods and backing means.

2. A double concrete column form comprising inner and outer vertical corner rods, straight horizontal tie rods connected between the inner corner rods and between the outer corner rods, and horizontal tie rods formed with bent portions intermediate their ends, one end of each of the latter rods connected to an inner corner rod, the bent portion of said rod engaging the inner corner rods on the same side of the form and the other end of said rods connected to the outer corner rod nearest to the last named inner corner rod.

3. A double concrete column form comprising inner and outer vertical corner rods, straight horizontal tie rods formed with hook

ends connected between the inner corner rods and between the outer corner rods, and horizontal tie rods formed with hook ends and intermediate bent portions, one hook end of each tie rod connected to an inner corner rod, the bent portion of said rod engaging the inner corner rod on the same side of the form and the other hook end of said tie rod engaging the outer corner rod nearest to the last named inner corner rod.

4. A side frame for double concrete column forms composed of vertically spaced horizontal tie rods formed with hook ends, each tie rod bent near one hook end to form a curved rod engaging portion and from which said hook end projects at an oblique angle, and a backing sheet attached to said tie rods between their other ends and their curved portions.

20 5. A side frame for double concrete column

forms composed of vertically spaced horizontal tie rods formed with hook ends, each tie rod bent near one end to form a curved rod engaging portion and from which said hook end projects at an oblique angle, and vertical base rods secured to said tie rods between the other hook ends of the latter and their curved portions. 25

6. A reinforced column comprising inner and outer vertical corner rods, straight horizontal tie rods connected between the inner corner rods and between the outer corner rods, and spacing rods, each spacing rod engaging two inner corner rods on its respective side of the column and an outer corner rod on said 30 35 column side.

In witness whereof I have hereunto set my hand this 20th day of November, 1926.

JESSE B. PIATT.
